UNITED STATES PATENT OFFICE.

VINCENT NIZNANSKY, OF BETHLEHEM, PENNSYLVANIA.

KEY.

Application filed January 22, 1927. Serial No. 162,837.

This invention relates to improvements in keys and has particular reference to a door key protector.

The primary object of the invention resides in a key for use in hotels and like public places for preventing a guest or a person from forgetting to turn in the key with the clerk in charge when leaving the hotel, which often results in a loss to the proprietor of such establishment, as it is a common practice for such guests to unconsciously carry the key away in his or her pocket or purse.

Another object of the invention is to provide a key attachment which makes it awkward for a person to insert the key into the pocket of a garment or in a hand purse, so that it is necessary to hold the key which will act as a reminder to the party to turn the same over to the key clerk before leaving the hotel.

Another object of the invention is to provide a key having a weighted arm swingingly mounted on the stem thereof so as to normally hang downward when the key is inserted in the lock, and which arm co-acts with the key to make it noticeable upon attempting to insert the same in the pocket.

A further object of the invention is to provide a key protector which is simple in construction, easy to apply to a key and inexpensive of manufacture.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved key.

Figure 2 is a vertical longitudinal sectional view therethrough.

Figure 3 is a detail perspective view of the key sections separated.

Referring more particularly to the drawing, the reference numeral 10 designates my improved key protector in its entirety and which includes a key proper 11 of the type commonly used for hotel rooms and like public places and which key is constructed of a pair of separable sections 12 and 13.

The section 12 has a manipulating head 14 at one end thereof and a tapering socket 15 provided in its other end. The section

13 comprises a stem 16 having the usual web 17 at one end thereof, while the opposite end is tapered as at 18 to fit within the socket 15 of the section 12. A collar 19 is provided on the stem 16 in spaced relation to the tapered portion 15 and against which an arm 20 engages, and which arm is held by the end of the section 12. The arm 20 is swingingly mounted on the stem 16 by providing the said arm with an opening 21 adjacent one of its ends to receive the stem 16, and through which the stem is inserted before applying the section 12. When assembled, a rivet 22 is passed through the walls of the socket and the tapered end 15 of the section 13 to prevent the sections from pulling apart.

The lower end of the arm 20 is enlarged and weighted as at 23 to cause the same to automatically hang downward when the key is inserted in the lock of a door. To prevent the weighted end of the arm from swinging and possibly striking the door jamb and causing injury thereto, I provide a rubber bumper 24 which is in the form of a disk mounted on the lower end of the arm and the peripheral edges of the disk project beyond the sides and end of the said arm. The top end of the arm is provided with an opening 25 to allow the same to be hung up upon a hook when not in use.

Although, I have specifically mentioned that the key protector is primarily intended for hotel use, it will be appreciated that the same may be used upon any key if it is necessary that a particular key be kept from the pocket of a user when not in use.

From the foregoing description, it will be seen that the key is provided with three prominent protruding parts, namely, the opposite ends of the key and the lower weighted end of the swinging arm which makes it awkward and difficult for a person to unconsciously insert the key in his pocket. Should a person attempt to insert the key into his pocket, the inability to easily insert the same will arouse suspicion and cause the person to remember that it must be turned in to the custodian of the key. Should a person accidentally succeed in forcing the key into his or her pocket, the same will be discovered in a short time by reason of the unusual weight of the key.

If desired, the arm 20 may have suitable advertising indicia 26 thereon such as the name of the hotel or owner of the key and

room number, or any other suitable indicia. While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In a device of the class described, the combination of a key, an arm swingingly mounted on the stem thereof, and means for preventing longitudinal sliding movement of said key with respect to said arm.
2. In a device of the class described, the combination of a key, a weighted arm swingingly mounted on the stem thereof, and means for preventing longitudinal sliding movement of said key with respect to said arm.
3. A key comprising a pair of separable sections, an arm swingingly mounted on one of said sections and held against sliding movement by the other of said sections, and

means for securing said sections together.

4. A key comprising a pair of separable sections, an arm swingingly mounted on one of said sections and held against separation by the other of said sections, and means for securing said sections together, said means including a socket provided in one of said members for receiving one end of the other of said members and a fastening element passing through said members.

5. A key comprising a pair of separable sections, a weighted arm swingingly mounted on one of said sections and held against separation by the other of said sections, and means for securing said sections together, said means including a socket provided in one of said members for receiving one end of the other of said members and a fastening element passing through said members, and a yieldable cushion carried by the weighted end of said arm and extending beyond the side edges thereof.

In testimony whereof I have affixed my signature.

VINCENT NIZNANSKY.
